Primary Examiner — Cynthia M Chin(74) *Attorney, Agent, or Firm* — Plumsea Law Group, LLC(57) **CLAIM**

The ornamental design for a construction set element, as shown and described.

DESCRIPTION

FIG. 1 is a top perspective view of a construction set element showing the new design;

FIG. 2 is a bottom perspective view of the construction set element of FIG. 1;

FIG. 3 is a front elevational view of the construction set element of FIG. 1;

FIG. 4 is a rear elevational view of the construction set element of FIG. 1;

FIG. 5 is a right side elevational view of the construction set element of FIG. 1;

FIG. 6 is a left side elevational view of the construction set element of FIG. 1;

FIG. 7 is a top plan view of the construction set element of FIG. 1; and,

FIG. 8 is a bottom plan view of the construction set element of FIG. 1.

The broken lines and unshaded areas form no part of the claimed design.
